UNITED STATES PATENT OFFICE.

JOHN McNAUGHTON, OF LONDON, ONTARIO, CANADA.

STEREOTYPE-BLOCK.

1,177,196.

Specification of Letters Patent. Patented Mar. 28, 1916.

Application filed May 5, 1915. Serial No. 26,017.

To all whom it may concern:

Be it known that I, JOHN McNAUGHTON, a subject of the King of England, residing at London, in the Province of Ontario and 5 Dominion of Canada, have invented a new and useful Stereotype-Block, of which the following is a specification.

This invention relates to stereotype blocks, one of its objects being to provide a block 10 which can be kept on hand by a printer and to which he can readily attach stereotype plates whenever it is desired to use them, whereby it becomes unnecessary to provide a block for each stereotype plate. The general practice heretofore followed has been to mount stereotypes upon wooden blocks which are cast aside when the stereotype plates are of no further use, or else it has been the practice to form the stereotype 15 plates upon or secure them to metal blocks which have likewise been discarded with the plates. I am also aware of the fact that it is old to provide means for attaching plates to blocks, which blocks can be subsequently used in connection with other 20 plates. These means, however, have all been found objectionable for the reason that considerable mechanism has been required in the construction and operation of the blocks, 25 or else it has been necessary to provide grooves in the backs of the stereotype plates, this adding materially to the cost of producing the plates.

One of the objects of the present invention is to provide a block to which a stereotype 30 plate can be attached readily, the block being formed in a single piece and the fastening means being of a form which can be readily procured at all times and used without requiring any special skill.

It is thought that the advantages in providing a block which can be used in connection with different stereotypes, successively, will be apparent to all skilled in the 35 art to which the present invention relates. By utilizing blocks of this type, it is possible to ship the plates without being mounted, thus effecting a considerable saving in the cost of transportation over those stereotypes which are fixedly mounted on the 40 blocks. While this has been possible with some forms of devices heretofore patented, it has been necessary either to use special forms of fastening devices, special tools for 45 assembling the parts, or blocks which, by reason of their intricate construction, have

been undesirable both because of their cost and their inefficiency. Thus they have not come into general use.

One object of the present invention is to provide a block which is simple in construction, cannot get out of order, and which affords an efficient backing to which a stereotype plate can be secured without mutilating the block and from which the plate can be readily removed whenever desired and another substituted therefor, the attaching and removing of the plate not requiring the use of any expensive fastening means or of any special tools.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings: Figure 1 is a perspective view of a block embodying the present improvements. Fig. 2 is a section on line A—B Fig. 1, and showing a stereotype plate secured in position. Fig. 3 is a section on line C—D Fig. 1, and showing a stereotype plate in position.

In forming a block such as constitutes the present invention, a light metal, such as aluminum, is preferably used. The block may consist of a face portion 1 and longitudinal reinforcing ribs 2. Obviously these blocks can be of any proportions desired. Formed within the face portion 1 of the block are slots 3 which extend throughout the width of the block and also downwardly desired distances into the ribs 2. The slots are preferably provided with flared upper portions 4. The slots can be extended diagonally within the face portion of the block as shown or if preferred, can be arranged in any other manner desired. For example the slots can be extended straight across from one side to the other or can be disposed in herring-bone formation. These modifications are so obvious that it is not deemed necessary to illustrate them in detail.

The means employed for attaching the

stereotype plate 5 to the block consists of ordinary wire nails of a diameter equal to the width of the narrowest portion of each slot 3. After the stereotype plate 5 has been properly placed on the blocks, the nails, which have been indicated at 6, are driven through the plates at points where they will enter certain of the slots 3. When the heads of the nails have been brought into engagement with the plate 5, those portions of the nails projecting below the slots are bent back toward the face portion of the block as shown particularly in Fig. 3, thus constituting efficient means for tying the plate 15 to the block.

In order to provide means whereby the nails can be readily bent, ribs 7 are preferably formed along the bottom of the face portion 1 of the block and at the sides of the 20 slots, as shown in Fig. 3, the nails being bent against these ribs as shown. By flaring the upper ends of the slots, the nails are properly guided into the slots during the driving operation. By utilizing diagonally disposed slots, it is always possible to find a 25 number of blank spaces on the stereotype plate located directly above certain of the slots so that there is never any difficulty in

placing the nails so as to properly secure the plate to the block without mutilating the 30 printing face. When the stereotype plate is to be discarded, it is merely necessary to bend the nails so that they can be withdrawn from the block, whereupon the plate can be removed and another plate substituted in the 35 manner hereinafter pointed out.

What is claimed is:—

1. A stereotype block including a face portion having slots therein, the upper portions of the slots being flared, and ribs extending along the sides of each slot, said ribs being arranged upon the bottom of the face portion of the block.

2. The combination with a block having slots in the face portion thereof and ribs along the sides of each slot and projecting downwardly from the face portion of the block, of a stereotype plate resting on the block, and bendable means extending downwardly through the plate and certain of the 45 slots and laterally into engagement with certain of the ribs.

In testimony that I claim the foregoing as my own, I have hereto affixed my signature.

JOHN McNAUGHTON.
